UNITED STATES PATENT OFFICE.

FRANZ OSCAR ADLER AND HERMANN JORDAN, OF MARKNEUKIRCHEN,
GERMANY.

WOODEN MUSICAL WIND-INSTRUMENT.

SPECIFICATION forming part of Letters Patent No. 550,431, dated November 26, 1895.

Application filed February 24, 1894. Serial No. 501,323. (No model.) Patented in Germany September 27, 1893, No. 83,005; in England October 31, 1893, No. 20,598; in France November 2, 1893, No. 233,792; in Italy March 30, 1894, XXVIII, 35,418, LXIX, 268, and in Austria-Hungary June 18, 1894, No. 11,724 and No. 22,743.

To all whom it may concern:

Be it known that we, FRANZ OSCAR ADLER and HERMANN JORDAN, of Markneukirchen, in the Kingdom of Saxony, Germany, have 5 invented a new and Improved Wooden Musical Wind-Instrument, (for which we have obtained the following patents: in Germany, No. 83,005, dated September 27, 1893; in England, No. 20,598, dated October 31, 1893; in 10 France, No. 233,792, dated November 2, 1893; in Austria-Hungary, No. 11,724 and No. 22,743, dated June 18, 1894, and in Italy, XXVIII, 35,418, LXIX, 268, dated March 30, 1894,) of which the following is a specification. 15 This invention relates to an improved wooden musical wind-instrument producing a rich and novel effect.

In the accompanying drawings, Figure 1 is a longitudinal central section of our improved 20 musical instrument; Fig. 2, a cross-section on line M M, Fig. 1; Fig. 3, an elevation of the instrument, and Fig. 4 an elevation taken from the opposite side.

The letter A represents the tubular wooden 25 body of the instrument, provided with a partition B², that forms two communicating wind-chambers B B'. The chamber B connects with a neck C, carrying the mouthpiece C'. The bore D of the neck C is smaller than the width 30 of chamber B at the point of connection, and in this way an offset E is here formed, which has an effect upon the novel sound produced.

The chamber B is contracted from the point 35 F upward, which is also of importance. The chambers B B' are closed at the bottom by plate G, while the arrangement of the keys is

similar to that used on the clarinet, bassoon, or oboe. At the top of chamber B' there is placed a metal sound-accumulator H. The bore of the instrument gradually widens from 40 the mouthpiece toward its end, with the exception of the contracted part F.

Our improved musical instrument can be played the same as the oboe or bassoon, and as the tone produced is entirely novel it may 45 be easily played by a musician and will produce a characteristic effect in the orchestra. It has the same peculiarity as the flute or oboe of producing the higher note of the octave on a forced blow. The tone is horn-like, very 50 strong, and of rich timbre, so that the instrument is particularly adapted for march or dancing music, where it will lead the tune. It is adapted for large and small (even the smallest) orchestras, is very durable, requires 55 no repairing, can be tuned in sharps and flats, and has a reach of almost three octaves.

What we claim is—

The combination of a tubular wooden body A, having partition B² and tapering wind 60 chambers B B', contracted at F, with nozzle C, having shoulder E, substantially as specified.

In testimony whereof we have signed our names to this specification in the presence of 65 two subscribing witnesses.

FRANZ OSCAR ADLER.
HERMANN JORDAN.
